(57) **CLAIM**

The ornamental design for an automatic baby formula mixing machine, as shown and described.

DESCRIPTION

FIG. 1 is a front elevation view of an automatic baby formula mixing machine showing my new design;
FIG. 2 is a rear elevation view thereof;
FIG. 3 is a right elevation view thereof;
FIG. 4 is a left elevation view thereof;
FIG. 5 is a top plan view thereof;
FIG. 6 is a bottom plan view thereof; and,
FIG. 7 is an isometric view thereof.
